UNITED STATES PATENT OFFICE

FREDERICK W. HOCHSTETTER, OF PITTSBURGH, PENNSYLVANIA

ELECTRON DISCHARGE DEVICE

Application filed March 27, 1930. Serial No. 439,280.

My invention relates in general to that type of electron discharge device including filament, grid and plate electrodes. In particular it relates to a device of this type in which 5 two grids are included instead of the usual single grid, the grids being so positioned and so connected into the circuit that they are always at opposite phase and so that the electron attracting or repelling effect of one is 10 complementary to that of the other with respect to the plate. By my invention I am able to secure increased plate voltage without increasing the plate impedance or introducing instability in the circuit.

15 One form of my invention is illustrated by the drawing, of which—

Figure 1 is a side elevation of a tube with the outer envelope partly broken away to show the arrangement of the electrodes; and 20 Fig. 2 is a diagram of a circuit to illustrate the manner in which the tube of Fig. 1 may be used.

Referring to Fig. 1 the device consists of 25 an evacuated enclosing envelope 1, preferably of glass, equipped with the usual base 2 through which the leads from the electrodes run to the usual prongs 3. Positioned within the envelope is a plate 4, preferably cylindrical in form, within which is the usual grid 5 and filament 6. A second grid 7 is mounted 30 within the filament 6. For convenience in manufacture and to insure proper spacing between the filament 6 and the grid 7 I prefer to provide the usual insulating and supporting stem 8 with a hollow cylindrical extension 9 of glass or other dielectric. The filament may conveniently be wound upon this extension, as shown, and the second grid 7 inserted within it after which the atmosphere 35 within extension 9 may be exhausted. Also the other grid 5 and the plate 4 may be supported in part by the projection 9, thus securing rigidity and permanence in the positioning of the electrodes. The usual leads are 40 carried in the usual way through stem 3 to the contact prongs 3, of which there are five instead of the usual four on account of the extra grid.

The tube which I have described is preferably employed in a circuit having the gen-

eral character of that illustrated by Fig. 2. In Fig. 2 the signal energy is impressed upon the tube through a transformer 10, one end of the secondary of which is connected to the grid 5 and the other end to the grid 7. Any 45 desired amount of bias may be imposed upon the grids by means of a C battery 11 in circuit between one side of the filament and a tap 12 in the secondary winding of transformer 10. The filament circuit is conventional, including the usual A battery 13, as is the plate circuit with its B battery 14.

As a result of this arrangement the two grids will always be in opposite phase and 50 since one grid is outside of the filament and one inside their action upon the passage of electrons from the filament to the plate will be either assisting or retarding. That is to say when grid 5 is positive it will aid the 55 flow of electrons from the filament to the plate. At the same time grid 7 will be negative and repellent to electrons, but because it is located upon the other side of the filament it will tend to drive the electrons toward the plate and, therefore, aid grid 5 in 60 this respect. Similarly, when grid 5 is negative and consequently repellent to electrons, grid 7 will be positive and attractive to electrons, with the result that one grid aids the 65 other in deceasing the flow of electrons to the 70 grid.

In this way the electronic action of the tube is magnified. In this way the two grids work 75 together to control the operation of the tube more effectively and more efficiently than is 80 possible with the ordinary single grid arrangement.

In the above description I have referred to 85 the grids as being "positive" or "negative" for the sake of simplicity. It will, of course, be 90 understood that these terms are used in an illustrative sense only and would more accurately be stated as "more positive" or "more negative" since it is not necessary for them to actually change their polarity to obtain 95 the desired effect.

Thus, without increasing the inter-electrode capacities or the internal impedance of the tube the amplification factor may be materially increased. Furthermore, by the use 100

of an input transformer having a center tap secondary winding, as shown in Fig. 2, the tendency towards feed-back through the common impedance of the A, B and C battery circuits is reduced. The reference to the A, B and C batteries is, of course, purely conventional since my device will operate with equal success with any suitable form of power pack or other device whereby batteries are 10 eliminated.

11 I claim:

- 12 1. An electron discharge device comprising an evacuated envelope, a plate and filament therein, a grid between said plate and filament, a dielectric stem within said filament and a second grid within said stem.
- 13 2. An electron discharge device comprising an evacuated envelope, containing a cylindrical plate, a grid within said plate concentric therewith, a filament within said grid and concentric therewith, and a second grid within said filament, said filament and said second grid being separated by a dielectric stem.
- 14 3. An electron discharge device comprising an evacuated envelope, containing a cylindrical plate, a grid within said plate concentric therewith, a filament within said grid and concentric therewith, and a second grid within said filament, said filament being wound upon a hollow dielectric stem, and said second grid being positioned within said stem.
- 15 4. An electron discharge device including an anode, a cathode and two grid electrodes, one of said grid electrodes being separated from the other electrodes by a dielectric in the form of an exhausted container.
- 16 5. An electron discharge device comprising an evacuated envelope, a plate and filament therein, a grid between said plate and filament, an exhausted dielectric stem within said filament, and a second grid within said stem.

17 In testimony whereof I have hereunto set
18 my hand on this 4th day of March, A. D.
1930.

FREDERICK W. HOCHSTETTER.
